METHOD OF ANESTHETIZING

Filed March 27, 1939

1. A method of anesthetizing body tissues which consists in applying to the tissue a fine stream of oxygen and a fine stream of a volatile liquid, the oxygen stream being directed against the surface of the tissue and the volatile liquid stream being directed against the same point under pressure, the oxygen stream meeting the volatile liquid stream at the tissue.

UNITED STATES PATENT OFFICE

Patent No. 2,258,863, issued Oct. 14, 1941, to Earle Wayne Reynolds, Serial No. 264,297, filed March 27, 1939.

METHOD OF ANESTHETIZING

Earle Wayne Reynolds, Grand Rapids, Mich., assignor of one-half to James A. Rickert, Grand Rapids, Mich.

Application March 27, 1939, Serial No. 264,297.

5 Claims.

(CL 128—173)

This invention relates to a method of and apparatus for anesthetizing body tissues. One place where the invention is particularly useful is in the extraction of teeth. Also it is useful in many other operations in dentistry as in drilling and otherwise working on teeth preparatory to filling cavities therein. There are many other places where tissues may be anesthetized other than in dentistry, and my invention in use is not to be specifically limited to any particular place or places of use.

One well-known way of anesthetizing tissues is to "freeze" them with a consequent deadening of nerves in the so-called frozen tissues which, thereupon, may be cut or otherwise operated upon without the production of the pain which would occur if the nerves in such tissues were alive and normally active. The so-called freezing is generally obtained by projecting a high volatile liquid against the surface of the tissue. Its rapid evaporation absorbs heat which is drawn from the tissues, with a resultant lowering of temperature and freezing of the tissues. The direct application of the volatile liquid alone against the tissues has heretofore been subject to the draw-back that the penetration of the anesthetization was very limited, so that for anything except merely surface work the freezing method of anesthetization was of little value.

With my invention there is directed against the tissue which is to be anesthetized a fine stream of the highly volatile liquid and also oxygen is simultaneously projected to the same point under pressure, the flow of oxygen and of the volatile liquid meeting at the tissue. It is to be understood that the oxygen may be intermingled with other gases, particularly inert gases such as nitrogen, so that ordinary air which is very largely a mixture of oxygen and nitrogen serves very well in lieu of oxygen alone.

My invention is directed to this process of anesthetization stated and to the provision of a very simple and practical apparatus for carrying out the method. I have found that with such method of anesthetization the anesthetic effect penetrates very materially into the tissues, so much so that in the extracting of teeth the penetration is sufficient to completely deaden the nerve of the tooth and also the tissues surrounding the roots of the tooth, whereby the tooth may be very quickly and readily extracted without pain to the patient.

An understanding of the invention may be had from the following description, taken in connection with the accompanying drawing, in which:

Fig. 1 is a side elevation of the apparatus of the invention, showing the container tube 1, the holder 5, the tube 8, the lever 3, the cap 4, and the tube 2.

Fig. 2 is a somewhat enlarged partial longitudinal section and side elevation of the holder for the volatile liquid and the attached tube which carries the oxygen or oxygen mixture.

Fig. 3 is a transverse section through the holder.

Fig. 4 is a view similar to Fig. 2, showing a slight modification for use with a somewhat different type of bottle holder for the volatile liquid, and

Fig. 5 is a fragmentary side elevation of the open end of the holder for the bottle.

Like reference characters refer to like parts in the different figures of the drawing.

The tube 1, of glass usually, at one end is constricted and has an outlet 2 with a small outlet opening through which a fine stream of the highly volatile liquid, for example, ethyl chloride, is projected. Adjacent this nozzle end 2 a spring actuated lever 3 is pivotally mounted which controls a closure cap 4 normally held over the open end of the nozzle end 2 to prevent escape of the liquid. But by operating the lever 3, as indicated in Fig. 1, to move the cap 4 out of the way, the liquid may be projected, such projection being caused by an evaporation of liquid within the tube 1 thereby generating pressure such that the liquid will be projected outwardly when the cap 4 is moved to open position in a fine continuous stream for a considerable distance. Such tubular holder for ethyl chloride or the like and the lever structure at the end described is very old and well-known.

In one form of the apparatus this tube is placed within a metal tubular holder 5 closed at one end and open at the other, within which adjacent its closed end a cushion of sponge rubber 6 is adapted to be located. The glass container 1 is inserted in the holder tube 5, as shown in Fig. 2, and is held at its inner end against the cushioning rubber 6 by a yielding coiled spring 7 connected at its ends to the flange 5a around the open end of the metal holder 5 as shown, the middle portion of the spring bearing against the outer end portion of the container tube 1; and the spring being stretched and tensioned, the container tube 1 is held within the metal holder 5. Alongside the member 5 a tube 8 of small diameter preferably of copper and having a small passageway therethrough is permanently secured. Such tube 8 has an integral section 9 extending therefrom and beyond and away from

the nozzle outlet 2. The flexibility of the copper tubing used permits the free section 9 to be bent as may be needed so that the paths of the volatile liquid out of the nozzle at 2 and of oxygen and air out of the free end of the section 9 of the tube, will come together at a selected point a distance beyond the outlet end of the section 9.

Oxygen compressed within a drum 10 or air compressed therein may be let out of the drum by opening a valve at 11. A flexible tubing 12 of rubber or the like connects the outlet of the drum 10 with the free end of the tubular section 8, as shown. Thus on opening the valve 11 the compressed air or oxygen will be ejected substantially in a straight line from the outlet of the section 9. Moving the cap 4 to its open position as in Fig. 1, the volatile liquid is projected in a stream indicated at 14; and the valve 11 being opened, air will be projected substantially in the path of the line at 15, the two paths 14 and 15, in the carrying out of my method, coming together substantially at the surface of the tissue 13 which is to be treated. Within a short time, the tissue is deadened against pain, "frozen" in other words to a considerable depth, and the nerves in such tissue to the depth that the anesthetization takes place are deadened and the tissue may be painlessly cut or otherwise operated upon.

In Fig. 4 the metal holder 16 is likewise closed at one end with a sponge rubber cushion 6 adjacent the closed end. A wall of the holder 16 near the open end is provided with a bayonet slot as at 17 (Fig. 5). The bottle 18 which contains the volatile liquid will be cast with a lug 19 which may pass down the bayonet slot, then on turning the bottle 18 and the holder 16 relative to each other, the lug 19 is located in the lateral branch of the bayonet slot. The bottle has an outlet nozzle at 20 normally capped by the cap 4 carried by the spring actuated lever 3. The flexible tube 8, the free end section 9, and the rubber tubing 12 connected with a compressed oxygen or compressed air drum are the same as before, the tube 8 being permanently mounted at one side of and lengthwise of the holder 16. This is substantially the same as the structure shown in Fig. 2, differing only in minor detail, but so far as the method is concerned, the simultaneous projection of the volatile liquid and the oxygen and air to the same point against a tissue which is to be treated is the same with both forms of apparatus.

The herein described method has proven to be exceptionally satisfactory in practice. The apparatus required is simple and easily constructed.

Having thus described my invention, what I desire to claim and secure by Letters Patent is as follows:

I claim:

1. The herein described method of anesthetiza-

tion which consists, in projecting a highly volatile liquid in a continuous stream against a selected portion of the surface of tissue to be anesthetized, and simultaneously directing a continuous stream of gas under constant pressure against said surface at substantially the same selected surface portion, so that the two streams will meet at substantially their point of contact on said tissue.

2. The herein described method of anesthetization which consists, in simultaneously directing a thin continuous stream of a highly volatile liquid and a stream of oxygen under constant pressure against a preselected portion of the surface of tissue to be anesthetized, so that the two streams will meet at substantially their point of contact on said tissue.

3. The herein described method of anesthetization which consists, in directing a thin continuous stream of a highly volatile liquid under constant pressure at a predetermined portion of the surface of tissue to be anesthetized, and concurrently directing a separate continuous stream of air containing oxygen under constant pressure against said surface of the tissue so as to meet said stream of liquid at substantially the same point of contact on said tissue.

4. The method of anesthetization which consists, in providing a container for a highly volatile liquid and having a small outlet therefrom from which a continuous thin stream of the liquid may be projected with a constant velocity, directing said stream of highly volatile liquid against a selected portion of the surface of tissue to be anesthetized and located at a distance from the point of outlet of said liquid from the container, and directing a separate small diameter tube toward said portion of the surface of the tissue and forcing oxygen through and out of the tube in a continuous stream concurrently with the flow of liquid out of said container, whereby the liquid and the oxygen meet at the selected portion of the surface of the tissue to be anesthetized.

5. In a construction of the class described, a holder for a container of highly volatile liquid, said container having a small diameter outlet beyond an end of the holder, means for closing said outlet adapted to be manually moved to open position, a bendable tube of small diameter connected to said holder and having a free end portion extending beyond the outlet end of the container, and means for selectively controlling the passage of an oxygen carrying gas through said tube, said bendable tube at its free section being capable of change of position so as to bring the path of the liquid projected from the container and of the gas passing from the tube into convergence at a preselected point beyond the outlet ends of said tube and container.
